UNITED STATES PATENT OFFICE.

FREDERICK M. FURBER, OF REVERE, MASSACHUSETTS, ASSIGNOR TO UNITED SHOE MACHINERY CORPORATION, OF PATERSON, NEW JERSEY, A CORPORATION OF NEW JERSEY.

MECHANISM OR APPARATUS FOR HOLDING OR TRANSFERRING ARTICLES.

Application filed December 21, 1918. Serial No. 267,783.

To all whom it may concern:

Be it known that I, FREDERICK M. FURBER, a citizen of the United States, residing at Revere, in the county of Suffolk and 5 State of Massachusetts, have invented certain Improvements in Mechanisms or Apparatus for Holding or Transferring Articles, of which the following description, in connection with the accompanying drawings, 10 is a specification, like reference characters on the drawings indicating like parts in the several figures.

This invention relates to a mechanism or apparatus for holding or transferring articles. The illustrated embodiment of 15 the invention is particularly designed for use in the manufacture of shoes for picking up pieces of material one at a time and delivering them in proper relation to a 20 sole or some other part of a shoe. However, it will be obvious that the invention is capable of wide application.

The primary object of the invention is to produce a novel mechanism of the character 25 above indicated which will be simple, efficient and reliable in construction and operation.

With this and other objects in view the invention comprises, in one aspect, a pair 30 of relatively movable members constructed, proportioned and arranged to grip exteriorly and transversely the endmost only of a stack of articles. Furthermore, the invention comprises certain combinations 35 and arrangements of parts, as well as various details of construction, which will be set forth in the following description of a preferred embodiment thereof and will then be pointed out in the appended claims.

40 Referring to the accompanying drawings, Fig. 1 shows in side elevation a picker embodying the invention in operative relation to a stack of articles to be transferred, certain parts being shown in section;

45 Fig. 2 is a similar view with the parts in a different relation; and

Fig. 3 is a detail view in perspective of one of the pivoted carriers or levers.

The mechanism herein shown by way of 50 illustration as embodying the invention has been particularly designed for use as an

element in a machine which applicant has invented for practising a method of making shoe bottoms which is the subject of his application for U. S. Patent, Ser. No. 55 203,802, filed November 4, 1917, the particular mechanism herein shown being employed to pick off a metallic shank piece from the top of a stack in a magazine, or supported on a table, and to deliver the shank 60 piece to an outsole. However, the mechanism may also be embodied in a simple tool supported by and operated in the hand and, therefore, the means for supporting and operating this mechanism forms no 65 part of the present invention and is not herein shown. Moreover, obviously the mechanism may be used for handling articles and blanks of numerous other kinds.

As shown in the drawings, the articles to 70 be transferred, viz; shank pieces 2, are arranged in a stack 4 upon a table or suitable support 6. Conveniently, the stack may be contained in a magazine 7 opposite side walls of which are slotted, as indicated 75 at 8, to receive the lower ends or jaws of levers 10 and to permit the removal of even the lowermost article from the stack. One of the two levers 10 which constitute the means for engaging the articles is shown 80 separately in Fig. 3. Intermediate between its ends each lever is provided with an ear 12 containing a hole 14 and the lower end of the lever is beveled at 16, the inner or upper end of the bevel merging into a sub- 85 substantially vertical surface 18 which, with an intersecting horizontal surface 19, forms a square shoulder to fit the edge of the article. The central portion of the lower end of the lever may be cut away as at 20 to 90 insure a proper engagement of the surface 18 with the edge of the article. The height of the shoulder is made approximately equal to, but preferably slightly less than, the height of the thinnest shank piece, or 95 other article, to be handled by the particular mechanism so that only one article may be gripped at a time by the jaws. The upper ends of the levers 10 are laterally offset and rounded as shown at 22. The ears 100 12 are each approximately one half the thickness of the ends of the levers and are

both pivoted upon the same pin or bolt 24 which is slidable in a slot 26 in the two opposite walls 27 of the bifurcated lower end of a carrier or slide 28. The lower end of the slide is formed as a foot 30 interposed between the lower ends of the levers 10 and constituting an ejector as will be more fully described. The upper portion of the slide 28 is shown as a rod. An elongated sleeve 32 is slidable thereon and is provided with an integral flange 34 pressed against the upper rounded ends 22 of the levers 10 by a coiled spring 36 which, at its upper end, bears against a collar 38 fixed by a set screw 40 to the rod or slide 28. The upper end of the slide may be provided with a grip or handle, if the mechanism is to be used as a hand tool, or it may be suitably connected to a crank arm or other appropriate transferring mechanism.

In the use of the mechanism for transferring shank pieces one by one from a stack 4 to some other location, such as an outsole 42, it will be presented to the stack 25 of shank pieces with the ends of the jaws extending a maximum distance beyond the lower end of foot 30 and with the inner faces of the jaws resting against the sides of the foot. Preferably, the slot 26 is so located that the lower end surface of the foot will be in alinement with, or just above, the horizontal surfaces 19. The surfaces 18 on the two levers will then be at a distance apart somewhat less than the width of the shank pieces 2 so that the beveled faces 16 of the jaws engage the upper edges or corners of the topmost shank piece. As a downward pressure is exerted upon the picker through the slide 28, these beveled faces are forced downward and outward until the shank piece is seated against the surfaces 19, as shown in Fig. 1. The strength of the spring 36 is sufficient to insure a preliminary flattening out and 45 pressing together of the shank pieces in the stack before the jaws spread apart. The offset upper ends 22 of the levers are acted upon by the flange 34 at a substantial distance laterally from the axis 24 so that 50 the spring tends normally to force the jaws toward each other and against the sides of the foot 30. As shown in Fig. 1, the topmost shank piece 2 has been firmly clamped between the jaws of the levers 10, upon the 55 release of the downward pressure on the slide and, by the bodily upward movement of the picker, the shank piece thus clamped and held by friction alone may be transferred to any desired point. The height of 60 the shoulders 18, 19 is preferably such, as already pointed out, that only one shank piece can be removed from the stack at a time.

As shown in Fig. 2, the shank piece while 65 thus clamped may readily be discharged

from the picker upon a sole 42, or other surface wider than the distance apart of the lower ends of the jaws. When the picker approaches the sole 42 the lower ends of the jaws first come into contact with its upper surface whereupon the continued downward movement of the slide relative to the jaws causes the foot 30 to force the shank piece 2 positively from between the surfaces 18 and directly down against the upper surface of the sole 42 as shown in Fig. 2. Thereafter, when the picker is lifted, the shank piece is left lying upon the sole. By repeating the operation thus described, all the shank pieces may be removed successively from the stack 4 and delivered to different soles.

It is to be noted that the particular shape and proportions of the lower ends of the levers 10, constituting the gripping jaws, are of considerable importance, not only in order to insure the removal of only one shank piece at a time from the stack but also because, owing to the beveled surfaces 16 of the jaws, the shank piece, after it has been delivered to the sole, cannot be picked up again by the jaws as the picker is lifted.

Having thus indicated the nature and scope of the invention and having described in detail a preferred form of mechanism in which it may be embodied, what I claim as new and desire to secure by Letters Patent of the United States is:

1. Mechanism of the class described having, in combination, a pair of levers movable about a common axis and having provision for holding an article, a support upon which said levers are pivoted but movable longitudinally relative thereto, yielding means constantly tending to move said levers relative to each other, and a part connected with said support for limiting such movement of said levers.

2. Mechanism of the class described having, in combination, a pair of levers, a single pin upon which the levers are pivoted, a slide having a slot to receive said pin and a spring interposed between a part of the slide and the ends of the said levers and constantly tending to move said levers relative to each other.

3. Mechanism of the class described having, in combination, a pair of levers movable about a common axis and having provision for holding an article, a slide upon which said levers are pivoted but movable longitudinally relative thereto, yielding means constantly tending to move the levers relative to each other and a foot also movable relative to the levers to eject an article held thereby.

4. Mechanism of the class described having, in combination, a pair of carriers constructed and shaped at corresponding ends to grip an article exteriorly, yielding means

constantly tending to move the carriers to gripping position and an ejector movable relative to the carriers to discharge an article held thereby.

5. Mechanism of the class described having, in combination, a pair of jaws movable toward and from each other, a spring for relatively moving the jaws to grip an article yieldingly and an ejector for discharging 10 the article from the jaws.

6. Mechanism of the class described having, in combination, a pair of jaws movable toward and from each other and shaped to engage opposite edges of an article, a spring

15 for relatively moving the jaws to grip the article yieldingly and an ejector movable longitudinally between the jaws for discharging the article therefrom.

7. Mechanism of the class described comprising a pair of relatively movable members constructed, proportioned and arranged to grip exteriorly and transfer the endmost only of a stack of articles.

8. Mechanism of the class described comprising means constructed and arranged to grip and transfer the endmost only of a stack of articles, said means including a pair of relatively movable surfaces for engaging opposite edges of the article.

30 9. Mechanism of the class described comprising a pair of jaws having co-operating surfaces for engaging opposite edges of an article, and a beveled surface merging directly into each such surface.

35 10. Mechanism of the class described comprising a pair of jaws movable toward and from each other and having surfaces shaped and arranged to engage opposite edges of an article and also beveled surfaces merging directly into said surfaces and shaped and arranged to guide the article into gripping position between said surfaces as the mechanism is brought into engagement with the article.

45 11. A picker comprising a pair of relatively movable jaws beveled at their ends and having a relatively shallow recess with substantially square shoulders at the inner ends of the bevels, said shoulders merging 50 with said bevels and being constructed and arranged to engage opposite edges of an article.

55 12. A picker for transferring a relatively rigid article having substantially parallel edges comprising a pair of pivoted levers the outer ends of which constitute jaws which are inwardly beveled and are provided with a relatively shallow recess having square shoulders, means tending to force said jaws toward each other so that when the bevels are pressed against opposite edges of the endmost of a stack of articles it will be clamped in said recess.

60 13. Mechanism of the class described comprising a pair of jaws constructed and ar-

ranged to grip opposite edges of the endmost only of a stack of articles in combination with additional means for engaging an article gripped by the jaws and ejecting it therefrom.

70 14. Mechanism of the class described comprising a pair of relatively movable jaws provided with shoulders for engaging opposite edges of an article, a slide movable bodily relative to said jaws and having a part by which an article clamped between said shoulders will be engaged and positively ejected from the jaws as the slide is moved relative to said jaws.

75 15. Mechanism of the class described comprising a pair of pivoted levers beveled at their ends and having a relatively shallow recess with square shoulders for engaging opposite edges of an article and a slide movable bodily relative to said levers and having a part movable into said recess by which an article clamped between the shoulders may be ejected therefrom.

80 16. Mechanism of the class described having, in combination, a pair of levers movable about a common axis and having provision for holding an article, a slide upon which said levers are pivoted but movable longitudinally relative thereto, an elongated sleeve having a sliding fit upon said slide and bearing against the ends of said levers and a spring acting upon the sleeve and constantly tending to move it and the levers relative to the slide.

85 17. Mechanism of the class described comprising a pair of pivoted levers beveled at corresponding ends and having a relatively shallow recess with square shoulders at the inner ends of the bevels, means constantly tending to move said shoulders toward each other to grip an article by its edges and a support for said levers movable bodily relative thereto, said mechanism being constructed and arranged to pick off the endmost of a stack of articles of the same width 100 to which it is presented and then to deliver such article to a surface of substantially greater width.

105 18. The combination of relatively movable members, 10, having bevels, 16, at corresponding ends, inwardly extending and shoulders, 18, 19, adjacent to the inner extremities of said bevels, together with an ejector, 30.

110 19. Mechanism of the class described having, in combination, a pair of levers constructed and arranged to hold an article, yielding means constantly tending to move the levers relative to each other to grip an article and hold it by friction alone, and a foot also movable relative to the levers to 115 eject an article engaged thereby.

120 20. Mechanism of the class described comprising a pair of relatively movable jaws constructed and arranged to grip an article, a slide upon which said jaws are supported 130

and which has an integral foot to eject an article from between said jaws.

21. Mechanism of the class described having, in combination, a pair of levers movable about a common fulcrum pin but being otherwise fixed relative to the pin and having provision for holding an article, a support having a slot in which said pin is slid-

able, and a spring acting against said support and against the ends of said levers and constantly tending to move said levers relative to each other.

In testimony whereof I have signed my name to this specification.

FREDERICK M. FURBER.

Certificate of Correction.

It is hereby certified that in Letters Patent No. 1,438,480, granted December 12, 1922, upon the application of Frederick M. Furber, of Revere, Massachusetts, for an improvement in "Mechanisms or Apparatus for Holding or Transferring Articles," an error appears in the printed specification requiring correction as follows: Page 3, line 116, claim 18, strike out the word "and" and insert the same to precede the word "inwardly" in the same line; and that the said Letters Patent should be read with this correction therein that the same may conform to the record of the case in the Patent Office.

Signed and sealed this 23d day of January, A. D., 1923.

[SEAL.]

KARL FENNING,
Acting Commissioner of Patents.
